UNITED STATES PATENT OFFICE

HENRY HENIG, OF BROOKLYN, NEW YORK

AUTOMATIC SPOUT FOR FLUID CONTAINERS

Application filed September 27, 1928. Serial No. 308,827.

This invention relates to containers for fluids and more particularly to a spout normally carried within the container and adapted to be automatically moved into position whereby the contents of the container may be poured through the spout.

An object of this invention is to provide a container having an opening therein adapted to be closed by the usual screw cap and having a preferably arcuate spout arranged within the container and adapted to be automatically moved through said opening when the cap is removed.

Another object is to provide a device of the character referred to having novel means for moving the spout through the opening in the container.

A further object is to provide a device of the character referred to having a vent pipe secured to the spout and extending into the container and adapted to communicate with the interior of the container and the atmosphere when the spout is in its outward position.

A further object is to provide a device of the character referred to having a guide member depending into the container adjacent the opening to assist in guiding the spout in its movements.

Other objects and advantages will be apparent from the following description.

In the drawings I have shown several embodiments of the invention. In this showing:

Figure 1 is a perspective view of a container showing the spout in its outer position,

Figure 2 is a sectional view taken substantially on line 2—2 of Figure 1,

Figure 3 is a perspective view of the spout,

Figure 4 is a sectional view taken substantially on line 4—4 of Figure 1,

Figure 5 is a vertical sectional view of a modified form of the invention without the spring,

Figure 6 is a horizontal sectional view of the modified form, and

Figure 7 is a perspective view of the modified form of spout and guide member.

Referring to the drawings the numeral 10 designates a container for fluids, such as lubricating oils and the like. The container is provided with a suitable handle 11 preferably secured to the top 11' thereof. Preferably adjacent one corner, the top 11' is provided with an opening 12 which may be closed by the usual screw cap 13.

A preferably arcuate spout 14, tapered as shown at 15 and provided with an annular flange portion 16 adjacent its lower extremity is adapted to be normally carried within the container as shown by dotted lines in Figure 2.

Means are provided for moving the spout 14 through the opening 12 into a position whereby the contents of the can may be poured through the spout, upon removal of the screw cap 13. As shown in Figures 2 and 4, a coil spring 17 is arranged inwardly of the container and has one arm 18 thereof rigidly secured to the top of the container as shown at 19. The other arm 20 of the spring is relatively long and extends slightly beyond the opening in the container when the spout is in its outer position. The coil spring 17 is tensioned whereby the arm 20 thereof will normally urge the spout 14 through the opening 12 in the container. The flanged portion 16 of the spout is provided with a substantially semi-annular extension 21 having 80 a relatively wide peripheral slot 22 therein, through which the arm 20 of the spring is adapted to extend.

In order to guide the spout in its movement into and out of the container, a preferably arcuate guide member 23 depends into the container from the top thereof adjacent the opening 12, and this member is provided with a vertical slot 24 through which the arm 20 of the spring also extends. As clearly

shown in Figure 2 the free end of the arm 20 is turned downwardly as shown at 25 to prevent the arm from accidentally disengaging the spout when the latter is in its inner position, as shown by dotted lines in Figure 2.

In the form of the device shown in Figures 5, 6 and 7 the spout 26 is provided with a passageway 27 through which a portion of a vent pipe 28 is adapted to extend, and the latter is adapted to communicate between the interior of the container and the atmosphere when the spout is in its outer position to insure a free flow of fluid from the container. As shown in Figure 7 the guide member 29 is provided with two substantially vertical slots 30 and 31. The longer arm of the coil spring is adapted to extend through the slot 31 as in the form of the invention previously described, and the vent pipe 28 is movable in the slot 30 when the spout is being moved to either its inner or outer position.

The operation of the device is believed to be apparent. In the form of the invention shown in Figures 1 to 4 inclusive the spout 14 is adapted to be normally carried within the container and is held in place therein by the screw cap 13. When it is desired to pour the contents of the can, the cap 13 is removed and the arm 20 of the spring 17 will urge the spout through the opening 12 and into a position whereby the contents of the can may be poured through the spout. The flanged portion 16 of the spout engages the inner side of the top of the container and forms a fluid proof joint adjacent the opening 12, thus preventing fluid from escaping at any place other than through the spout. The flanged portion limits the outward movement of the spout but does not prevent the spout from being turned in a horizontal plane for a distance equal to the length of the slot 22. The outer extremity of the spout preferably extends beyond the sides of the container and this extremity of the spout may be rotated in a horizontal plane through an arc of approximately 90°.

The arm 20 of the spring extends through the slot 24 in the guide member and through the slot 22 in the extension and this arm is movable in said slots when the spout is moved to its inner or outer position, as will be apparent.

The operation of the device as shown in Figures 5, 6 and 7 is substantially the same as the previously described operation except that the vent pipe 28 is slidable in the slot 31 during the movement of the spout.

In both forms of the invention the spout may be moved in a horizontal plane when in its outer position, through an arc of substantially 90°. This movement of the spout is regulated by the length of the peripheral slot in the extension, as will be apparent. The upper portion of the slot 30 is enlarged to per-

mit the vent pipe to turn when the spout is turned in a horizontal plane.

It is to be understood that the forms of my invention herewith shown and described are to be taken as preferred examples of the same, and that various changes in the shape, size, and arrangement of parts may be resorted to without departing from the spirit of the invention or the scope of the subjoined claims.

I claim:

1. A device of the character described comprising a container having an opening therein, a spout arranged within said container and movable through said opening, said spout being provided with a depending portion having a slot therein, a guide depending into said container adjacent said opening and having a slot therein, and spring means slidable in both of said slots to normally urge said spout through said opening.

2. A device of the character described comprising a container having an opening therein, a spout arranged within said container and movable through said opening, said spout being provided with a portion to limit its movement through said opening, an extension depending from said portion and having a slot therein, a guide depending into said container adjacent said opening, said guide being provided with a slot therein, and spring means slidable in both of said slots to normally urge said spout through said opening.

3. A device of the character described comprising a container having an opening therein in adjacent one corner thereof, an arcuate spout arranged within said container and movable through said opening to a position whereby the outer extremity of said spout will extend beyond the sides of said container, a guide depending into said container adjacent said opening and provided with a slot therein, and spring means slidable in said slot to normally urge said spout through said opening.

4. A device of the character described comprising a container having an opening therein adjacent one corner thereof, an arcuate spout arranged within said container and movable through said opening to a position whereby the outer extremity of said spout will extend beyond the sides of said container, said spout being provided with an extension having a slot therein, a guide depending into said container adjacent said opening and having a slot therein, and a spring arranged within said container and having a portion extending through both of said slots to normally urge said spout through said opening.

5. A device of the character described comprising a container having an opening therein adjacent one corner thereof, an arcuate spout arranged within said container and movable through said opening to a position whereby the outer extremity of said spout

will extend beyond the sides of said container, said spout being provided with a portion to limit its movement through said opening, an extension depending from said portion and having a slot therein, a guide depending into said container adjacent said opening, said guide being provided with a slot therein, and a spring arranged within said container and having a portion extending through both of said slots to normally urge said spout through said opening.

6. A device of the character described comprising a container having an opening therein, a spout arranged within said container and movable through said opening, a vent pipe secured to said spout and adapted to communicate between the interior of the container and the atmosphere, a guide depending into said container adjacent said opening, said guide being provided with a pair of slots therein, and a spring arranged within said container and having a portion extending through one of said slots to normally urge said spout through said opening, said vent pipe being movable in the other of said slots.

7. A device of the character described comprising a container having an opening therein, a spout arranged within said container and movable through said opening, said spout being provided with a depending extension having a slot therein, a vent pipe secured to said spout and adapted to communicate between the interior of the container and the atmosphere, a guide depending into said container adjacent said opening and being provided with a pair of slots therein, and a spring arranged within said container and having a portion extending through said first mentioned slot and one of the slots in said guide to normally urge said spout through said opening, said vent pipe being movable in the other slot in said guide.

8. A device of the character described comprising a container having an opening therein, a spout arranged within said container and movable through said opening, said spout being provided with a portion to limit its movement through said opening, an extension depending from said portion and having a slot therein, a vent pipe secured to said spout and adapted to communicate between the interior of the container and the atmosphere, a guide depending into said container adjacent said opening and being provided with a pair of slots therein, and a spring arranged within said container and having a portion extending through said first mentioned slot and one of the slots in said guide to normally urge said spout through said opening said vent pipe being movable in the other slot in said guide.

9. A device of the character described comprising a container having an opening therein, a spout normally carried within said con-

tainer and movable through said opening, said spout being provided with a depending extension having a slot therein, a guide depending into said container adjacent said opening and having a slot therein, and a spring arranged in said container and having an arm adapted to extend through both of said slots to normally urge said spout through said opening, the free extremity of said arm being turned downwardly to prevent accidental disengagement from said extension.

In testimony whereof I affix my signature.
HENRY HENIG.
